UNITED STATES PATENT OFFICE.

FRANK E. SHAFFER, OF ST. LIBORY, NEBRASKA, ASSIGNOR OF ONE-HALF TO WILLIAM PLACKE, OF ST. LIBORY, NEBRASKA.

AUTOMOBILE LIGHT PLUG.

Application filed May 12, 1928. Serial No. 108,597.

The present invention relates to an automobile light plug such as is used for connecting the electric conductors to headlights and the like.

5 The advantages of this improvement are, first the elimination of the screw used in the present light plug, and the possibility of losing the screw when attaching the wire, secondly, time saved in attaching and 10 detaching the wire and insuring a positive contact.

An important object of the invention is to provide a plug of this nature which is exceedingly simple in its construction and 15 may be placed on the market at a very low cost.

Another very important object of the invention lies in the provision of a plug of this nature which will prove thoroughly efficient and reliable in use, and is capable of 20 withstanding the wear and tear incident to its use.

With the above and numerous other objects in view as will appear as the description proceeds, the invention resides in certain novel features of construction, and in the combination and arrangement of parts as will be hereinafter more fully described and claimed.

25 In the drawing:—

Figure 1 is a perspective view of my improved plug.

Fig. 2 is a longitudinal section through the improved plug with the housing engaged 35 thereon, and

Figs. 3 and 4 are transverse sections taken substantially on the lines 3—3, and 4—4 respectively, of Fig. 2.

Referring to the drawing in detail, it will 40 be seen that the numeral 5 denotes the cylindrical shell of the plug formed of suitable insulating material and having the cylindrical bore 6. One end of the insulating shell 5 is threaded as is indicated at 7 for engagement with a protective housing 8 of the usual formation. A pair of diametrically 45 opposed pins 9, project radially from the exterior surface of the shell 5 for engagement with the usual bayonet slots found in 50 the sockets of automobile headlights and the like.

The numeral 10 denotes a solid contact shank which extends through the bore 6 of the shell 5 for engagement in the well known manner with the contact of a socket. This

shank 11 merges into a cylinder 11 which is slotted to provide a slot 12 having a free spring bridge formed thereacross as is indicated at 13, said bridge being, of course, integral with the cylinder. The extremity 60 of the cylinder is formed into a spring clip including a pair of ogee shaped spring arms 14.

The single or double conductor 15 is led thru the opening 16 in the protective housing 8 in the usual manner. The conductor to engage the contact 10 is passed between the spring arms 14 and looped about the spring bridge 13. It will be seen that this engagement is accomplished with very 70 little effort and very quickly in comparison to the usual engaging means now in common use. There is practically no likelihood of the conductor 15 coming loose from the contact 10 as is quite apparent. It is thought 75 that the construction, utility, and advantages of this invention will now be clearly understood by those skilled in this art without a more detailed description thereof.

The present embodiment of the invention 80 has been disclosed in detail since in actual practice it attains the features of advantage enumerated as desirable in the statement of the invention and the above description. Changes in the details of construction may 85 be resorted to without departing from the spirit or scope of the invention as herein-after claimed, or sacrificing any of its advantages.

Having thus described my invention, what 90 I claim as new is:—

1. A plug of the class described including a cylindrical shell having a bore, a solid contact bar in the bore and merging at one end into a cylinder provided with a slot having an integral bridge extending thereacross, and said cylinder terminating in a pair of spring clip arms of ogee formation.

2. A plug of the class described including a cylindrical shell having a bore, a solid contact bar in the bore merging at one end into a cylinder provided with a slot having an integral bridge extending thereacross, said cylinder terminating in a pair of spring clip arms of ogee formation, and a protective housing threaded on the end of the shell about the cylindrical portion of the contact.

3. As a new article of manufacture, a contact for a plug of the class described including a solid cylindrical shank portion merg-

105 110

ing at one end into a concentric cylindrical extension, a portion of the cylindrical extension being slitted and bent inwardly to provide a diametrically extending spring bridge and the extremity of said cylinder merging into ogee shaped spring clip arms formed by slitting the extremity of the cylinder longitudinally and bending said portions inwardly toward each other.

5 4. As a new article of manufacture, a contact for a plug including a cylindrical shank

one end of which is hollow, said hollow end being slitted and bent inwardly to provide a diametrically extending spring bridge, and the extremity of said hollow end merging 15 into ogee-shaped spring clip arms formed by slitting the extremity of the hollow portion longitudinally and bending said portions inwardly towards each other.

In testimony whereof I affix my signature.

FRANK E. SHAFFER.
